UNITED STATES PATENT OFFICE.

JACOB M. BUZARD, OF PITTSBURGH, EVERSON P. COLE, OF CORAOPOLIS, AND FRANK H. HASLAGE, OF PITTSBURGH, PENNSYLVANIA.

PROTECTING DEVICE FOR AIR-BRAKE-PIPE COUPLINGS.

1,154,481.

Specification of Letters Patent. Patented Sept. 21, 1915.

Application filed April 2, 1915. Serial No. 18,740.

To all whom it may concern:

Be it known that we, JACOB M. BUZARD, EVERSON P. COLE, and FRANK H. HASLAGE, citizens of the United States, residing at 5 Pittsburgh, Coraopolis, and Pittsburgh, respectively, in the county of Allegheny, State of Pennsylvania, have invented certain new and useful Improvements in Protecting Devices for Air-Brake-Pipe Couplings, of 10 which the following is a specification.

Our invention consists of mechanism for protecting terminals of air pipes of an air brake or other system of fluid circulation in car service.

15 Ordinarily, the air pipes of the car are provided with rigidly mounted terminals, to which are attached the hose sections having the terminal couplings, and such terminals are apt to be struck by the couplers 20 of approaching cars in coupling, and injured or destroyed, especially in coupling on curves, or where the drawbars are for any reason thrown out of normal alinement.

25 In our invention, we provide for the mounting of the end portions of the pipes in such a manner as to provide for their automatic backward movement, utilizing flexible connections and springs so arranged as to adapt exposed portions of the line to be depressed and resiliently returned, as herein-after more fully described.

30 In the drawings, which show two adaptations of the invention, Figure 1 is a plan view, showing the couplers of adjacent cars in abnormal position, and in contact with the pipe terminals. Fig. 2 is a view showing the construction in elevation. Fig. 3 is a similar view, illustrating a modified arrangement. Fig. 4 is a detail view, showing 35 a modified construction as to the mounting of the supporting spring. Figs. 5 and 6 are detail views, showing the supporting plate for the spring and its connection with the pipe.

40 Referring to the construction of Figs. 1 and 2, the coupler heads 2, 2, of well-known construction, are mounted by their drawbars in the central framework of the cars, and when coupling on curves, or when thrown 45 out of alinement for any reason, are apt to strike the terminal 3, having the usual valve and stem 4 and to damage the same.

45 In carrying out the invention, we provide between the outer end of the rigidly mounted pipe section 5 and a longitudinally mov-

able section 6 a section of hose 7, which is connected with the pipes 5 and 6 with a coupling terminal 8 at each end. Between these terminals 8 and surrounding the hose section 7, is a coiled or helical spring 9, the terminals of which pass through lugs 10 of couplings 8 and are wound one or more times around pipes 5 and 6, providing good connection. Pipes 5 and 6 are supported by hangers 11, 12, respectively, pipe 6 having the longitudinally slidable bearing in hanger 12, so that when terminal 3 is struck it will slide backwardly and avoid injury. Upon release of pressure, a spring 9 will effect retraction of the section 6, thrusting it outwardly to its normal position, the whole section straightening out, under action of the spring, as will be readily understood.

50 In Figs. 3 to 6 inclusive, we show a modified arrangement in which the several parts are the same as above described, and indicated by the same numerals having the exponent "a." In place, however, of the hanger 12, the front section 6^a may be supported in a depending plate 12^a, beyond which extends a spring 9^a bearing against a collar 13. A similar collar 14 is secured around pipe 6^a behind hanger 12^a to positively limit the outward movement, collar 13 acting to utilize the resiliency of the spring in thrusting pipe section 6^a outwardly. Hose section 7^a, by its resiliency, is free to buckle under the compressive action, and to be reerected or straightened in the same manner as above described. The front portion of pipe 6^a is supported by a helical spring 15, preferably in coniform arrangement, having the terminal loop 16 engaging pipe 6^a, the upper coil of the spring being supported in a plate 17, which is bolted up underneath the end sill of the car. Said plate 17 is provided with a groove 18 around its upper face, in which lies the upper coil of spring 15, one end of which is turned downwardly through the plate, as at 19, fixedly holding it in position, the coil passing downwardly at an angle through a suitably formed opening 20, as clearly shown.

55 As shown in Fig. 6, the lower end of the supporting spring 15^a is provided with a depending staple or loop 21 secured by U-bolts 22 to the terminal of the wire, whereby to provide an easy supporting bearing for the section 6^a.

When spring 15 is attached to a steel car 110

structure, as in Fig. 4, a separate supporting plate 17^b is secured on the inner side of the front sill 23, connected with a supporting spring 15^b in the same manner as above described. The advantage of the spring 15, as thus hung, or from plate 17, as described, is that it allows for a considerable range of deflected movement of section 6^a in any direction, the loop 16 at the same time providing for an easy sliding support in carrying out the main functions of the invention.

The advantages of the invention will be readily understood and appreciated by all those familiar with this class of construction.

It completely obviates the liability to breakage or injury; it maintains the coupling terminals at their normal position without in any way preventing or affecting their operation or manipulation in coupling or uncoupling, and it effects a very material saving of cost in time and preventing breakage of the parts.

The invention may be variously changed or modified by the skilled mechanic to suit the conditions of use, but all such changes are to be considered as within the scope of the following claims.

What we claim is:

30 1. In a protecting device for air brake couplings, the combination with a rigid conducting pipe, of an outer coupling pipe and terminal, a support therefor permitting longitudinal movement of the coupling pipe, a

hose coupling device on the inner end of the 35 coupling pipe and the outer end of the conducting pipe each provided with a lug, a connecting hose section connected at each end with said coupling device, and a coiled spring surrounding the hose section and having its end portions engaging said lugs and coiled around the pipes beyond said coupling devices.

2. In a protecting device for air brake couplings, the combination with a rigid conducting pipe, of an outer coupling pipe and terminal adapted for longitudinal, lateral and vertical movement, a hose section connecting the rear end of the coupling pipe with the front end of the conducting pipe, a coiled spring adapted to be depressed on backward movement of the coupling terminal and to expand to return said terminal to normal position, and a helical spring depending from the car framing provided with a looped terminal loosely engaging the coupling pipe and adapted to move laterally and vertically with it and to provide for longitudinal movement therein.

In testimony whereof we have hereunto affixed our signatures in the presence of two witnesses.

JACOB M. BUZARD.
EVERSON P. COLE.
FRANK H. HASLAGE.
